UNITED STATES PATENT OFFICE.

FENTON D. CRAIG, OF MEMPHIS, TENNESSEE.

TRACE-CARRIER.

1,304,743.

Specification of Letters Patent. Patented May 27, 1919.

Application filed November 6, 1916. Serial No. 129,759.

To all whom it may concern:

Be it known that I, FENTON D. CRAIG, a citizen of the United States, residing at Memphis, in the county of Shelby and State 5 of Tennessee, have invented certain new and useful Improvements in Trace-Carriers, of which the following is a specification.

My invention relates to trace carriers arranged to carry the traces of a draft-animal, 10 and to be adjustable lengthwise of the back-band, for adjustably supporting the traces at various elevations. My improved device is also employable for other purposes.

Devices of the character described are usually 15 made of metal, which is subject to corrosion, caused for instance, by the action thereon of the perspiration of the draft-animal upon which the same is used, with the result that the corroded face of the device, 20 contacting and abrading the animal, causes injury to its hair and hide.

It is the object of my invention, to provide a device of the character described so arranged and operating that it is removed 25 from contact with the animal; further, to provide a device of the character mentioned with novel means for engaging the band, whereby injury to the band is avoided; and the invention will be further readily understood 30 from the following description and claim, and from the drawing, in which:

Figure 1 is a perspective view, showing my improved device in position for use.

Fig. 2 is a front elevation of my improved 35 device, showing the same attached to a back-band.

Fig. 3 is a longitudinal section of the same, taken on the line 3—3 of Fig. 2.

Fig. 4 is an edge elevation of the same.

Fig. 5 is a cross-section of the same, taken 40 on the line 5—5 of Fig. 2; and,

Fig. 6 is a rear elevation of the same.

11 represents the back-band, usually of canvas, leather or other flexible substance. 45 12 represents the base of my improved device, which is preferably stamped out of a single piece of sheet-metal. The base is provided with cross-slots 13, 14 forming end cross-strips 15, 16. The band is arranged 50 to be passed from the rear of the base through one of the cross-slots, and from the front of the base in reverse direction through the other of the cross-slots, the intermediate portion of the band crossing the intermediate 55 portion of the base between the cross-slots 13, 14.

The intermediate portion of the base is provided with a recess 17, which is shown as a substantially wide recess. Cross-strips 18, 19, are located between the recess 17 and 60 the respective cross-slots 13, 14. The recess 17 is preferably shorter than the cross-slots 13, 14, the cross-slots 13, 14, extending laterally beyond the ends of the recess 17.

The respective ends of the base are bent 65 transversely to the base for forming upturned ends 20 of the base, provided with ears 21 at the respective ends of the base.

A pivoted clamp 25 is provided with trunnions 26 received in bearing-holes 27 in the 70 ears 21. The clamp is preferably formed up out of a single piece of sheet-metal. It is provided with a reversely bent substantially wide cross-tongue 28, bent from the body 29 of the clamp by means of a bend 30. The 75 free end of the cross-tongue and its lateral edges are preferably straight and plain, and when the clamp is in clamping position the cross-tongue is preferably in the plane of the cross-strips 18, 19, and of the margin- 80 portions 31 of the base between the recess 17 and the upturned ends 20, the margin-portions being between the respective ends of the slots 13, 14. The side face of the tongue passes into the recess 17 and is presented toward the face side of the band. 85

When the band is clamped in the device, a portion 32 thereof is pushed through the recess 17 by the side face of the tongue, the tongue being surrounded by said band, the 90 band extending and being clamped entirely around the edge of said tongue, between the edge of said tongue and the marginal walls of said recess at the top and bottom and at the respective ends of said recess, (see Figs. 95 3 and 5), with the side edges of the band extending across the margin-portions 31, forming a very effective clamp which does not injure the band.

The base is provided with a hook 35 extending therefrom, which is arranged to receive the draft-chain 36 or other supported part. The clamp is provided with a handle 37 having an inturned flange 38 received across the open end of the hook 36 when the 100 clamp is closed, for retaining the part held by the hook within the hook.

The upturned ends 20 are turned upwardly in manner to provide the base with curved ends 39, so that end contact between 110 the device and the animal may not injure the animal.

It will be further noted from Figs. 3 and 4, that the portions of the inner face 40 of the back-band which contact the animal are distanced at all points from the plane of the 5 rear face of the device, so that contact between the metal of the device and the animal is avoided, and that all points of possible contact with the animal, either of the device or of the connections of the back-band with 10 the device, are by means of rounded portions for avoiding injury to the animal.

My improved device further provides an exceptionally strong, durable and simple device, which is economically made, and 15 further provides a device which securely holds the band and prevents injury thereto.

Having thus fully described my invention, what I claim as new and desire to secure by Letters Patent, is:

20 A trace carrier or similar device, comprising a base provided with cross-slots through which a flexible band may be passed,

said base further provided with an intermediate cross-recess across which the band may extend, said cross-slots extending outwardly 25 farther than said cross-recess, said cross-recess having clamping walls at both its sides and at both its ends, and a clamp provided with a tongue which when clamped extends in a plane substantially parallel with and is 30 located in the plane of said base, with the side face of said tongue arranged to project into said cross-recess in contact with and parallel with the face side of the flexible band to force the band through said recess 35 against all said walls.

In testimony whereof I have hereunto signed my name in the presence of two subscribing witnesses.

FENTON D. CRAIG.
